SHOE LENGTHENING TOOL

James Ventola, Kansas City, Mo.

Application January 29, 1934, Serial No. 708,851

4 Claims. (Cl. 12—123.1)

My invention relates to improvements in shoe lengthening tools.

One of the objects of my invention is to provide a novel tool with which the upper of a shoe 5 may be lengthened, and the upper rear edge portion of the vamp expanded and pushed forwardly, when desired.

A further object of my invention is to provide a novel tool of the kind described, which is simple, cheap, strong, durable, not likely to get out of order, which is easily and quickly operated and not liable to damage the shoe operated upon, and which is efficient in operation.

The novel features of my invention are hereinafter fully described and claimed.

In the accompanying drawings, which illustrate my invention,

Fig. 1 is a side elevation of one form of my improved tool, shown mounted in operative position in a shoe, which is shown in longitudinal vertical section.

Fig. 2 is a plan view, partly broken away and enlarged, of the tool shown in Fig. 1.

Fig. 3 is an enlarged front elevation of the heel member shown in Figs. 1 and 2.

Fig. 4 is a view, partly in plan and partly in horizontal section, of the toe member and parts connected therewith, of a modified form of my invention.

Fig. 5 is a side elevation of what is shown in Fig. 4.

Fig. 6 is a rear elevation of the toe member shown in Fig. 4.

Fig. 7 is a side elevation, enlarged, of the vamp engaging member shown in Fig. 1.

Fig. 8 is a top view of the same.

Fig. 9 is a front elevation of the same.

Fig. 10 is a view partly in side elevation and partly in vertical longitudinal section, and partly broken away, of another modification of my invention.

Fig. 11 is a plan view, partly broken away, of what is shown in Fig. 10.

Fig. 12 is a rear end view, partly broken away of the toe member shown in Figs. 10 and 11.

Fig. 13 is a view similar to Fig. 11, but showing another modification of my invention.

Fig. 14 is a rear end view of the toe member shown in Fig. 13.

Fig. 15 is a view similar to Fig. 4, showing still another modification of my invention.

Fig. 16 is a rear end view of the toe member shown in Fig. 15.

Fig. 17 is a vertical sectional view of a modifi-

cation of the heel engaging member and part of the pushing member, shown in side elevation.

Fig. 18 is a top view of what is shown in Fig. 17. Similar characters of reference designate similar parts in the different views.

Referring to Figs. 1 to 3, 1 designates a toe member adapted to be inserted into the toe of a shoe 2, and to bear against and push forwardly the inner side of the toe portion of the shoe upper 3. 4 designates a heel member adapted to bear against the inner side of the rear end of the upper 3, and which is provided near its upper end with a forwardly and rearwardly extending hole 5, Fig. 2, which is screw threaded and which has rotatably fitted in it the screw threaded shank 6 of a pushing member. Said shank 6 extends rearwardly through the heel member 4 and at the rear thereof is provided with a transverse operating handle 7 by which the shank 6 may be axially rotated in the heel member 4.

The rear end of the toe member 1 has a central ear 8, at opposite sides of which are respectively disposed two forwardly extending arms 9 of a connecting member 10, which is pivoted to swing on a transverse horizontal axis by a pin 11 extending transversely and horizontally through the arms 9 and the ear 8.

The rear end of the connecting member 10 is provided with a longitudinal hole which extends clear through the connecting member 10 and has axially rotatably mounted therein the reduced front end portion 12 of the shank 6. Said front end portion is provided with a rearwardly extending threaded hole in which is fitted a screw 13, the head of which is larger than the hole and engages the connecting member 10 between the arms 9, thus holding the connecting member rotatably connected to the shank 6.

Upon mounting the tool in the shoe, as shown in Fig. 1, with the heel member 4 bearing against the inner side of the rear part of the upper 3, and with the toe member 1 bearing against the inner side of the toe portion, the rotating of the shank 6 in the proper direction, by means of the handle 7, will cause the shank to travel forwardly through the heel member 4, if the latter is held from turning with the shank, thereby, through the connecting member 10 and pin 11 forcing the toe member 1 forwardly, thereby stretching the upper 3, due to the forcing of the toe and heel members further apart.

The toe member 1 and the heel member 4 are, preferably shaped so as to approximately fit those portions of the upper which they engage, so as to

hold these members from a turning movement when the screw shank 6 is axially rotated.

To expand the rear edge portion 14 of the vamp and stretch it forwardly, when desired, I provide 5 a vamp engaging member, shown in Figs. 1, 7, 8 and 9.

Said vamp engaging member is provided with a shank 15 adapted to be removably mounted between the arms 9 and at the rear of the ear 8. 10 At the upper end of the shank 15 is provided a head 16 adapted to rest on the arms 9 and to move therewith, and adapted to have its hooked upper end portion engage the rear edge portion 14 of the vamp, and to force the latter forwardly 15 when the screw shank 6 is turned so as to advance the toe member 1 and connecting member 10.

In Figs. 4, 5 and 6, the toe member 17 is similar to the toe member 1, excepting that it has an ear 18 separable therefrom but attached thereto, 20 and connected pivotally to the connecting member 10, by a pin 11, similarly to the connection of the ear 8 to the arms 9 in Fig. 1. The member 17 may be of wood, and the ear 18 of metal if it is so desired.

25 In the form shown in Figs. 10 to 12, there is provided a toe member 19, of a shape and size adapting it for the shoes on which it is to be operated, and having a chamber on its under side, as shown. The shank 6', corresponding to the shank 6 already described, has a reduced front end portion 20 extending through and, preferably loosely fitted in a hole 21 extending through the rear wall of the toe member 19. The forward end of the portion 20 is shouldered and has fitted 30 on it a nut 22 bearing against the shoulder and which holds the shank 6' engaged with the toe member 19, while permitting the shank to axially rotate therein and to swing vertically.

The tool shown in Figs. 10 to 12 is operated in 40 a manner similar to that described with reference to the form shown in Fig. 1.

In the form shown in Figs. 13 and 14, 23 designates a toe member having attached to its rear end a bearing member 24 in which is axially rotatable and vertically oscillative the reduced front end portion 20 of a threaded shank 6', corresponding to that shown in Figs. 10 and 11, and having similarly mounted on its front end shouldered portion a nut 22 disposed in a recess 25 in the rear end of the toe member 23. This form of my invention is operated similarly to the form shown in Figs. 10 and 11, the shank 6' being extended through a threaded hole in a heel member corresponding to the heel member 4, and the rear end 50 of the shank 6' having affixed to it at the rear of the heel member a handle 7, similar to that shown in Figs. 1 and 2.

In the modification shown in Figs. 15 and 16, 60 the toe member 26, corresponds to the toe member 1, excepting that it is provided with two ears 27 at its rear end. A connecting member 28 is pivoted on a horizontal transverse axis to and between the ears 27 by a transverse pin 29. The rear end of the connecting member 28 has a longitudinal hole extending forwardly to a squared vertical opening 30 extending through the connecting member 28. In said longitudinal hole is axially rotatably fitted the reduced front end portion 20 of a threaded shank 6', corresponding to the shank 6' shown in Figs. 10, 11 and 13. A nut 22 is mounted on the shouldered front end portion of the portion 20 in the opening 30. The latter is adapted to receive the shank 15 of the 70 vamp engaging member shown in Figs. 1, 7, 8 and 75

9, and the head 16 of said member is adapted to rest removably on the upper side of the connecting member 28.

When it is desired to stretch the vamp portion 14 without also stretching the toe portion of the 5 vamp, the head 16 of the vamp engaging member may be disposed, and have a form such that it will engage and stretch the vamp portion 14 before the toe member engages the toe portion of the vamp, or the toe member may be operated 10 simultaneously with the head 16 to effect stretching.

In Figs. 17 and 18 is shown a modified form of heel engaging member comprising a body 31, which may be wood having a rearwardly extending hole therethrough, 32, into which extends a rearwardly extending tubular portion 33 of a plate 34 fastened to the front side of the body 31. The hole through the tubular portion 33 and plate 34 is threaded and has axially rotatable 20 therein the screw threaded shank 6, corresponding to the shank 6, shown in Figs. 1 and 2. The heel member, comprising the parts 31 and 34, may be substituted for the heel member 4, with the side of the body 31 opposite the plate 34 employed to bear against the inner side of the rear part of the upper 3, as does the rear side of the heel member 4, as shown in Fig. 1.

Other modifications of my invention within the scope of the appended claims, may be made 30 without departing from the spirit of my invention.

What I claim is:—

1. A shoe lengthening tool comprising a toe member and a heel member shaped to respectively fit against the inner sides of and to be held from turning by the heel and toe portions of a shoe upper, a pushing member revoluble in and having threaded engagement with said heel member, means connecting said toe member with 40 said pushing member by which the latter may be axially rotated relatively to and, when rotated in the proper direction, to push said toe member forwardly, and means actuated by said pushing member for engaging and forcing forwardly the 45 rear edge portion of the vamp of the shoe.

2. A shoe lengthening tool comprising a toe member and a heel member shaped to respectively fit against the inner sides of and to be held from turning by the toe and heel portions of a 50 shoe upper, a pushing member revoluble in and having threaded engagement with said heel member, a connecting member pivoted on a horizontal axis to said toe member and with which said pushing member has axial rotary engagement, and a vamp engaging member carried by and movable forwardly with said connecting member and adapted to engage and push forwardly the rear edge portion of the vamp of the 55 shoe.

3. A shoe lengthening tool comprising a toe member and a heel member adapted to bear respectively against the inner sides of the toe and heel portions of a shoe upper, a pushing member having rotary threaded engagement with said heel member, a connecting member attached to said toe member and with which said pushing member has rotary axial engagement, and adapted to be pushed forwardly by said pushing member when the latter is axially rotated in the proper direction in said heel member, and the latter is held from turning, and a vamp engaging member carried by and movable forwardly with said connection member and adapted to engage and 70

push forwardly the rear edge portion of the vamp of the shoe.

4. A shoe lengthening tool comprising a toe member and a heel member adapted to respectively bear against the inner sides of the toe and heel portions of a shoe upper, a pushing member having rotary threaded engagement with said heel member, a connecting member pivoted on a horizontal axis to said toe member and with

10 which said pushing member has axial rotary en-

gagement, and which is adapted to be pushed forwardly, when said pushing member is axially rotated in the proper direction and said heel member is held from turning, and a vamp engaging member removably mounted upon and adapted to move forwardly with said connecting member, and adapted to engage and push forwardly the rear edge portion of the vamp of the shoe. 5
